HARRY P. MAUGHLIN, OF COLUMBUS, OHIO.

METHOD AND APPARATUS FOR CASTING IN CLOSED MOLDS.

Application filed September 6, 1922. Serial No. 586,513.

In the past, in casting it has been the practice to convey the molten metal from the furnace to the mold in open ladles, particularly when a sand mold was used. This method was disadvantageous, especially where small, sharp and flawless castings were desired, because the metal cooled, while transporting it, to such a degree that it was sluggish and would not fill the mold properly. It also made it necessary to provide relatively large gates, which not only allowed impurities such as slag or dross to get into the casting, but were difficult to remove, thus increasing the cost of the completed casting.

Furthermore, the height of the sprue determined the head pressure of metal in the mold and, if the volume or drop of the metal was too great, it would cause washing of sand into the casting causing flaws. When too small a sprue or gates were used, the metal was cooled to such an extent by its contact with the mold that it would freeze before filling the mold.

My invention has primarily to do with the method of making castings in closed sand molds, the sprue of which is brought into direct contact with the pouring nozzle of the furnace. This novel method prevents outside air from coming in contact with the molten metal and oxidizing it.

One of the objects of my invention is the complete control of the temperature of the metal as it is poured into the mold and also the volume of flow and head pressure. This accurate control makes it possible to secure very small, sharp and flawless castings with very small gates, which can be easily and cheaply removed without damage to the casting. These small gates have a further important function in that they aid in keeping dross, slag and other impurities out of the mold, acting as a sort of strainer, thus reducing imperfect castings to a minimum.

Another object of my invention is practically filling the mold at comparatively low velocity and light head pressure, to obviate the washing of sand into the casting or forcing the mold apart, and afterward quickly increasing the pressure to complete the filling of the mold, while the temperature of the metal is sufficiently high to flow freely. This will insure a casting that is sharp, clean cut and of full size.

A further object of my invention has to do with clearing the pouring nozzle of the furnace of metal and preventing it from freezing therein.

Various other features of my invention will be apparent as this description progresses and will be brought out in the claims appended hereto. The various objects of my invention are preferably obtained by the structure illustrated in the drawings, wherein similar characters of reference designate corresponding parts, and wherein—

Figure 1 is a side elevation of my novel furnace and mold in their cooperative relation.

Figure 2 is a cross-section on line 2—2 of Figure 3 of my furnace nozzle in contact with the sprue plate of the mold.

Figure 3 is a front elevation of the sprue plate.

Figure 4 is a side elevation of my furnace and mold in pouring position.

Figure 5 is a cross-section of my furnace and mold, showing the manner of obtaining increased head pressure after the mold is filled.

Figure 6 is a front elevation of my furnace structure showing the manner in which it is supported by the frame.

In the drawings, my apparatus for casting in a closed mold is shown as comprising a substantially spherical furnace 1, divided as at 2 for convenience in lining, and held together by suitable fastenings. The furnace 1 is provided with a charging opening 3, a hinged cover 4, and a truncated conical projection 5, wherein is held the pouring nozzle 6.

The furnace is provided with a large hollow trunnion 7, as best shown in Figure 6, having an opening 8 for some suitable form of heating unit for melting the charge, and a small trunnion 9 which is supported by the frame bearing 10. The trunnion 7 is supported by rollers 11 carried in the bracket 12, which is in turn supported by the frame member 13.

Depending from the lower part of the furnace are wings 14 to which are secured the track-like members 15. It is obvious that the furnace can be tilted about its horizontal axis and will carry the track-like members 15 with it. To facilitate the tilting of the

furnace I have provided the handle 16 fastened to the trunnion 7 of the furnace by the lug 17.

The furnace structure is supported in a horizontal position by a support bar 18, pivoted as at 19 to the frame 13, notched as at 20 to coact with the support rod 21 connecting the rails 15 near their outer ends. Adjacent the lower end of the support bar 18 is provided a foot 22 which coacts with the floor when in its disengaged position. It is evident that tilting the furnace in a backward direction a sufficient distance will raise the track 15 and release the support rod 21 from the notch 20 and allowing the bar 18 to swing outwardly and downwardly about its pivot 19 until the foot 22 stops further motion by coming into contact with the floor. The furnace structure can then be tilted forward to any desired position, the support rod 21 clearing the bar 18.

Resting on the track members 15, I have provided a car 23 which supports a table 24 at an appreciable angle, as shown in Figure 1, by means of a ball and socket connection 25. Secured to the table 24 by suitable clamps 26 is provided a conventional flask 27, having a mouth-like sprue plate 28, for the sprue opening 29, clamped thereto as at 30.

The ball and socket connection 25 allows a limited adjustment of the table 24 and flask 27, for the purpose of aligning the mouth-like sprue plate 28 with the pouring nozzle 6. The car 23 may then be moved toward the furnace sufficiently to bring the mouth-like sprue plate 28 into cooperative relation with the pouring nozzle 6 as best shown in Figure 2.

It will be noted that the nozzle 6 fits the mouth-like sprue plate 28 with a ball and socket union which permits of considerable adjustment and still allows close conjunction, for the exclusion of outside air. This is a very desirable feature as it prevents excess oxidization of the molten metal and makes practicable close regulation of the temperature of the metal as it enters the mold. It is further seen that the orifice 32 in the nozzle 6 is tapered throughout its length to facilitate its being cleared of foreign substances or metal which has "frozen" therein.

The flask 27 is held in pouring relation to the furnace by some suitable means such as shown in Figure 1, comprising upstanding bars 33 and a wedge-like block 34, which is forced between said bars 33 and the flask 27 to hold the mouth-like sprue plate 28 thereof in coacting relation with the nozzle 6. The upstanding bars 33 are vertically slideable in the channel structures 35 and are held against tilting by the pins 36. The channel structures 35 are secured to the track-like members 15 adjacent their outer

ends. I have provided hook-like projections 37 near the upper ends of the bars 33 which allow of their being lowered until the hooks 37 rest upon the upper edges of the channels 35, after the wedge 34 is withdrawn for the removal of the flask 27.

The level of the molten metal is held substantially on the line 38 by additions, from time to time, through the charging opening 3.

It will be evident that at times there is a possibility of metal freezing in the passage 39 of the sprue plate 28. To facilitate the removal of such frozen metal, I have divided the sprue plate 28 on the line 40. The two halves are held together by the bolt 41 and the nut 42 threaded thereto. I have also provided a dowel 43 which assists in holding the two halves in proper correlation to each other and in preventing any rotation of one half in relation to the other.

The operation of my novel form of apparatus for casting in a closed mold is as follows:

The molten metal being at proper temperature in the furnace, the mold is brought into proper cooperative relation and securely fastened. The handle 16 is raised, tilting the furnace backward until the support rod 18 is released, whereupon the handle is lowered with a continuous motion at a suitable speed through the position shown in Figure 4 and to substantially the position shown in Figure 5.

When the nozzle 6 becomes lower than the metal line 38, in the tilting operation, the metal fills the mold under a light head pressure, the flask 27 being substantially in a horizontal position as shown in Figure 4. The filling of the mold under light head pressure is very important as it obviates washing sand in the mold or swelling the casting due to the velocity of the metal and yieldability of the sand. It therefore insures against a swelled or enlarged casting.

The continued tilting to the position shown in Figure 5 brings a comparatively high head pressure to bear upon the metal in the mold while still in a liquid state, thus forcing it under pressure to completely fill the mold. Owing to the fact that the temperature of the metal can be controlled so closely, the mold being in direct conjunction with the furnace, the gate openings can be made much smaller than usual. This is important as it facilitates the removal of the gates from the casting, thereby saving time and expense. The small gate openings have the further advantage of assisting in the prevention of slag, dross and sand from entering the casting as the mold is being filled.

The furnace is now tilted back to the dotted line position, shown in Figure 1, and the metal from the nozzle and some from the sprue, which being comparatively large and

close to the furnace and therefore still in a liquid state, flows back into the furnace. The metal does not flow back from the casting itself, as sufficient time is allowed, before the above clearing of the nozzle operation, for the metal to "freeze" in the gates, thus holding the casting intact. The furnace is then tilted down to its original position, resting upon the support 18, which is moved into cooperative relation with the support rod 21 by hand.

It will be seen that the volume of flow is under complete control of the operator, through the speed at which the furnace is tilted. It is obvious that my novel furnace and mold structure is applicable to a considerable range of metals and various kinds of castings but it is particularly advantageous when sharp and clear cut castings are desired.

Having thus described my invention, what I claim is:

1. In casting apparatus, a furnace, a mold, and a common means for moving the said furnace and mold relative to each other.

2. In casting apparatus, a furnace tilttable about a horizontal axis, a mold pivotally mounted adjacent said furnace, and a common means for moving the said furnace and mold relative to each other.

3. Casting apparatus comprising a furnace provided with an outlet tilttable about a horizontal axis, a mold provided with an inlet pivotally mounted adjacent the outlet of said furnace, means for clamping the inlet of said mold against the outlet of said furnace, and means for moving the said furnace and mold relative to each other.

4. Casting apparatus comprising a furnace provided with an outlet tilttable about a horizontal axis, a nozzle disposed in said outlet, a mold provided with an inlet pivotally mounted adjacent the outlet of said furnace, means for clamping the inlet of said mold against the outlet of said furnace, and means for moving said furnace and mold relative to each other.

5. Casting apparatus comprising a furnace provided with an outlet tilttable about a horizontal axis, a nozzle disposed in said outlet, a mold provided with an inlet pivotally mounted adjacent the outlet of said furnace, means for clamping the inlet of said mold against the outlet of said furnace, and means for simultaneously moving said furnace and mold relative to each other.

6. Casting apparatus comprising a furnace provided with an outlet tilttable about a horizontal axis, a nozzle disposed in said outlet, a mold provided with an inlet pivotally mounted adjacent the outlet of said furnace, a sprue plate disposed about the inlet

of said mold and adapted to engage said nozzle, and means for moving said furnace and mold relative to each other.

7. Casting apparatus comprising a furnace provided with an outlet tilttable about a horizontal axis, a nozzle disposed in said outlet, a mold provided with an inlet pivotally mounted adjacent the outlet of said furnace, a sprue plate disposed about the inlet of said mold, means carried by said sprue plate to receive the said nozzle and hold same in substantially air tight relation, and means for moving said furnace and mold relative to each other.

8. In casting apparatus, a furnace, a mold, and means for moving the said furnace and mold together and relative to each other.

9. In casting apparatus, a furnace tilttable about a horizontal axis, a mold pivotally mounted adjacent said furnace, and means for moving the said furnace and mold together and relative to each other.

10. In casting apparatus, a furnace, a mold, and means for moving the said furnace and mold relative to each other and then moving both together.

11. In casting apparatus, a furnace tilttable about a horizontal axis, a mold pivotally mounted adjacent said furnace, and means for moving the said furnace and mold relative to each other and then moving both together.

12. The method of casting metals which comprises pouring at one pressure for a part of the pouring operation and then at an increased pressure for the balance of the pouring operation.

13. The method of casting metals in sand molds which comprises pouring the molten metal into a sand mold at one pressure for a part of the pouring operation and then at an increased pressure for the balance of the pouring operation.

14. A casting apparatus comprising a tilttable furnace, a track structure attached thereto, a car resting on said track and supporting a mold in universal relation thereto, and means for securing the mold in cooperative relation with the furnace.

15. A casting apparatus comprising a tilttable furnace, a track structure attached thereto, a car resting on said track and supporting a mold in universal relation thereto, a mouth structure for said mold in coacting relation with a removable furnace nozzle, and means for holding the mold and its mouth in cooperative relation to the furnace nozzle, while tilting the whole structure as a unit.

In testimony whereof I hereby affix my signature.

HARRY P. MAUGHLIN.
